US00D995724S

(12) **United States Design Patent** (10) **Patent No.:** **US D995,724 S**
(45) **Date of Patent:** **** Aug. 15, 2023**

(54) **SINK SIPHON**

(71) Applicant: **Nir Nahum**, Even Shmuel (IL)

(72) Inventor: **Nir Nahum**, Even Shmuel (IL)

(**) Term: **15 Years**

(21) Appl. No.: **35/514,127**

(22) Filed: **Oct. 28, 2021**

(80) **Hague Agreement Data**

Int. Filing Date: **Oct. 28, 2021**

Int. Reg. No.: **DM/217183**

Int. Reg. Date: **Oct. 28, 2021**

Int. Reg. Pub. Date: **Apr. 29, 2022**

(51) **LOC (14) Cl.** **23-01**

(52) **U.S. Cl.**

USPC **D23/266**

(58) **Field of Classification Search**

USPC D23/207-209, 314, 355, 370, 371, 414
